UNITED STATES PATENT OFFICE.

ALBERT E. PARK, OF MINNEAPOLIS, MINNESOTA

EXCAVATING-DIPPER.

1,047,135.

Specification of Letters Patent. Patented Dec. 10, 1912.

Application filed January 27, 1912. Serial No. 673,768.

To all whom it may concern:

Be it known that I, ALBERT E. PARK, of Minneapolis, Hennepin county, Minnesota, have invented certain new and useful Improvements in Excavating-Dippers, of which the following is a specification.

My invention relates to excavating dippers or shovels and particularly to that type in which the dipper is mounted on an arm 10 that is pivotally attached to a boom to allow the dipper to be drawn or pulled through the material to be excavated.

The primary object of my invention is to provide a dipper having a cutting edge 15 which can be drawn substantially parallel with the bottom line of the excavation.

A further object is to provide an excavating dipper that is easily controlled and operated.

20 A further object is to reduce the strain on the boom and the mechanism on which the boom is mounted as the dipper becomes filled with the excavated material.

The invention consists generally in a 25 frame pivotally connected to a boom, a dipper having its rear portion pivotally connected with said frame, and a sliding pivotal connection at its forward or receiving end with said frame, said sliding connection 30 permitting the raising and lowering of the cutting edge of the shovel.

In the accompanying drawings forming part of this specification, Figure 1 is a side view of a boom with the dipper attached, 35 ready to be dropped into the material to be excavated, the dotted lines showing the dipper as it breaks out of the excavation with a full load, Fig. 2 is an end elevation of the dipper attached to the boom, Fig. 3 is a side 40 view showing the dipper in its dumping position.

In the drawing, A represents the dipper and B the boom.

C and C' are the pairs of dipper arms. 45 The rear arms C are connected to the rear portion of the dipper by a hinge or pivot E and the lower ends of the arms C' are provided with radial slots G to receive headed bosses or lugs F which are mounted 50 on the forward portion of the dipper. The end walls G' of the slots G form stops to limit the movement of the bosses F therein. The arms C and C' are connected by suitable braces intermediate to their ends 55 and at their upper ends are joined together and pivotally attached to the boom B by a

pivot H. These arms form, therefore, in effect a skeleton frame pivotally connected with the boom and supporting the dipper. A loading line I is connected to the dipper, 60 preferably as near the cutting edge as possible, as indicated in Fig. 3, and the unloading line J is attached to the rear of the dipper by any suitable means, and preferably as near the lower edge of the dipper as is 65 practicable.

In operation, the shovel is brought to the position indicated by full lines in Fig. 1, the bosses F being at the upper ends of the slots G and the cutting edge of the shovel is 70 inclined forwardly and downwardly toward the bottom of the excavation. The cutting edge of the shovel with respect to the arms C and C', the position of the bosses F in the slots G, and the position of the dipper on 75 the pivot E, remain relatively the same until after the dipper passes the vertical dotted lines shown in Fig. 1, or a line drawn through the center of the pivot H. After passing this point, the cutting edge follows 80 the pull of the loading line I, the bosses F sliding down the slots G at their lower ends until they contact with the end walls G', the shovel swinging on the pivot E to allow this upward and backward tilting of the 85 dipper until it reaches the position indicated by dotted lines in Fig. 1. I thereby obtain a longer travel of the dipper on and parallel with the bottom line of the excavation and I am able to make a smooth excavation 90 with a minimum amount of power to fill the dipper and also greatly reduce the strain on the boom B.

I am aware that dippers are in use with arms rigidly secured to the dipper and 95 swinging on a pivotal connection with the boom. In an apparatus of this kind, the nearer the dipper approaches its full load position, the nearer the pull of the loading line is exerted parallel to the boom, thereby 100 decreasing the leverage. The cutting edge of the dipper with this arrangement assumes a position almost at right angles to the pull exerted by the loading line, causing a heavy strain on the boom and the machine to which 105 the boom is attached. This excessive strain greatly increases the cost of repairs to a machine of this kind and has been a serious objection to a dipper of that type. With my improvement the raising and lowering of the 110 cutting edge of the dipper is permitted and I am able to not only greatly reduce the

strain but dispense with a considerable portion of the power usually required to operate a dipper of this kind.

I claim as my invention:—

- 5 1. The combination, with a boom, of arms pivoted thereon, and a dipper having its rear portion pivotally connected with said arms and its forward portion slidably connected with said arms.
  - 10 2. The combination, with a boom, of arms arranged in pairs and rigidly secured together, the upper portions of said arms being pivotally connected with said boom, a dipper having its rear portion pivotally connected with the lower ends of one pair of arms and its forward portion slidably connected with the other pair of arms.
  - 15 3. The combination, with a boom, of arms pivoted thereon, a dipper having its forward and rear portions connected with said arms, loading and unloading lines for said dipper, the connections of the forward portion of said dipper with said arms allowing said dipper to rotate slightly and its cutting edge 20 to follow the pull of said loading line at a predetermined point in the travel of said dipper.
  - 25 4. The combination, with a boom, of arms arranged in pairs and pivoted thereon, said arms being secured together to form a rigid frame, a dipper having its rear portion pivotally connected to one pair of arms, the other pair of arms having curved slots in the lower ends thereof, bosses mounted on 30 the forward portion of said dipper and adapted to slide in said slots, and loading and unloading lines attached to said dipper.
  - 35 5. The combination, with a boom, of arms arranged in pairs and secured rigidly together and pivotally connected with said boom, a dipper having its rear portion pivotally connected with one pair of arms, the other pair of arms having longitudinal slots 40
- therein, bosses mounted on the forward portion of said dipper to enter said slots and slide therein, the end walls of said slots forming stops to limit the movement of said bosses, said bosses being normally at the upper ends of said slots but moving to the lower ends of said slots when said dipper 45 swings past the center of the pivots of said arms on said boom, and loading and unloading lines attached to said dipper.
6. The combination, with a boom, of a frame pivoted thereon, a dipper having its rear portion pivotally connected with said frame, the forward portion of said dipper having a limited sliding movement with respect to said frame at a predetermined point in the travel of said dipper. 50
7. The combination, with a boom, of a frame pivoted thereon, a dipper having its rear portion pivotally connected with said frame and its forward portion slidably connected with said frame, said sliding connection allowing said dipper to swing on its rear pivots after passing a vertical line drawn through the pivots of said frame on 55 said boom.
8. The combination, with a boom, of a dipper, means pivotally connecting the rear portion of said dipper with said boom, means connecting the forward portion of said dipper with said boom and allowing a limited rotary movement of said dipper on 60 said rear connecting means at a predetermined point in the movement of said dipper, and loading and unloading lines for said dipper.

In witness whereof, I have hereunto set my hand this 2d day of January, 1912.

ALBERT E. PARK.
